METHOD AND APPARATUS FOR CONDITIONING AND SUPPLYING WATER AND CARBON DIOXIDE TO CARBONATORS

Charles A. Getz, Glen Ellyn, Ill., assignor, by mesne assignments, to Reconstruction Finance Corporation, Chicago, Ill., a corporation of the United States

Application November 18, 1940, Serial No. 366,194

23 Claims. (Cl. 62—1)

This invention relates to methods of and apparatus for conditioning and supplying water and carbon dioxide to carbonators used in beverage bottling plants.

It is the present practice in beverage bottling plants to deliver to the carbonators water, which is suitable for human consumption, at temperatures which fall within a very narrow range, usually just above the freezing point. It is necessary to exercise this accurate control of the water temperature in order to obtain a constantly uniform, maximum amount of carbonation. Refrigeration, of course, is required to obtain this accurate control of the water temperature.

The carbon dioxide vapors are drawn from a bank of cylinders and delivered to the carbonators through pressure regulators which will drop the high pressure prevailing in the cylinders to the low pressure maintained in the carbonators. Accurate control of the pressure maintained in the carbonators is as important as accurate control of the water temperature. As the carbon dioxide vapors are withdrawn from the cylinders, the pressure in the cylinders is reduced. The replacement of exhausted cylinders with fully charged ones brings about a rise in pressure in the carbon dioxide vapor supply line. These constantly varying pressures make necessary a constant supervision over the pressure regulators or the desired uniform pressure will not be maintained in the carbonators.

The withdrawal of nothing but carbon dioxide vapors from the cylinders causes a corresponding amount of the remaining liquid to evaporate to replace the vapors which have been withdrawn. This vaporization brings about self-cooling or self-refrigeration of the remaining liquid. As the temperature of the remaining liquid drops, the vapor pressure in the cylinders drops correspondingly, resulting in need for further adjustment of the pressure regulators.

If the discharge of vapors from the cylinders continues at a proper rate and for a sufficient length of time, the temperature of the remaining liquid will be lowered to -70° F., the temperature at which the liquid will solidify. Further discharge from these cylinders cannot be obtained until absorption of heat from the surrounding atmosphere, or from some artificial source, causes sublimation of the solid carbon dioxide. Continuous discharge of about three-quarters of a starting charge in a cylinder will result in solidifying the remaining one-quarter.

In passing from the high pressure side to the low pressure side of a pressure regulator, the

5 carbon dioxide vapors are subjected to a throttling effect which produces a drop in temperature. Assuming that a constant pressure is maintained on the low pressure side of the regulator, the drop in temperature is in proportion to the reduction in pressure.

10 Carbon dioxide confined in the usual commercial cylinders is subject to and substantially corresponds with the temperature of the surrounding atmosphere. At temperatures ranging between 70° F. and 80° F., the vapor pressure of the carbon dioxide in cylinders will be between 854 pounds and 968 pounds per square inch absolute. The vapor pressure maintained in carbonators varies in different plants, but it is usually below 15 100 pounds per square inch. Therefore, it will be appreciated that plants will be operated, at least at certain periods, with pressure drops at the pressure regulators of as much as 700 or 800 pounds.

15 The cooling of the vapors resulting from the throttling effect produced by such large pressure drops will lower the temperature of the vapors below 32° F. and cause freezing of the water vapors, which frequently are found in relatively large amounts in carbon dioxide charged commercial cylinders, passing through the pressure regulators with the carbon dioxide vapors. As 20 freezing of water vapor causes faulty operation 25 of the pressure regulators, it is essential, therefore, to provide preheating means for superheating the vapors just before they are delivered to the pressure regulators.

The need for handling the heavy cylinders to 30 couple and uncouple the same with respect to the carbonator equipment, repairing the cylinder couplings, and maintaining the joints sealed against leakage in piping systems which, at times, are compelled to handle pressures in excess of 35 40 1000 pounds per square inch are items which any plant operator would be more than happy to dispense with.

The primary object of this invention is to provide methods and apparatus for supplying the required amount of water, at the desired constant temperature, to carbonators for beverage bottling plants with a considerably lower consumption of power required for refrigerating the water and for supplying the carbon dioxide vapors to the high pressure sides of the pressure regulators for the carbonators at a substantially constant pressure and thereby practically eliminate the attention formerly required by the regulators.

A still further important object of the invention is to maintain the carbon dioxide supply for

the carbonators in bulk storage, preferably a single insulated tank, and within relatively narrow, low vapor pressure and temperature ranges to permit the vapors to be delivered to the high pressure sides of the pressure regulators at the aforementioned substantially constant pressure. This constant pressure will be sufficiently close to the pressure at which the carbonators are operated to prevent the pressure drop within the regulators from providing sufficient cooling, as a result of the throttling effect produced by the regulators, to lower the temperature of the vapors to the freezing point of the small amount of water vapors present in the carbon dioxide obtained from said low temperature source of bulk supply.

Another important object of the invention is to maintain the carbon dioxide in said bulk storage within said relatively narrow low pressure range by withdrawing vapors from the storage tank until the pressure within the tank reaches the minimum value of the range and then withdrawing liquid from the tank until the pressure rises to the maximum value of the range as a result of normal heat input through the tank insulation and no self-cooling or refrigeration. During the periods when liquid is being withdrawn from the storage tank, it is necessary to change the withdrawn liquid to vapor before delivering it to the pressure regulators and their carbonators.

Still another important object of the invention is to pass the carbon dioxide vapors and liquid withdrawn from the bulk storage tank in heat exchange relation with some medium which will give up heat of vaporization to the liquid carbon dioxide and which will superheat the resultant vapors and the vapors obtained directly from the storage tank for delivery to the pressure regulators. The drinking water being delivered to the carbonators has been found to be an ideal medium for this purpose. Sufficient heat for accomplishing these desired results can be obtained from the drinking water and this absorption of heat from the water reduces the amount of refrigeration required to enable the water to be delivered to the carbonators at the desired low temperature.

Another object of the invention is to maintain the supply of carbon dioxide stored in bulk in an insulated tank and at a substantially constant low temperature and pressure so that the need for handling the heavy cylinders, repairing cylinder couplings, and maintaining joints in high pressure piping systems sealed against leakage is eliminated.

A further object of the invention is to charge the carbon dioxide into the bulk storage tank, as a liquid, at approximately the same low temperature and pressure prevailing in the tank and refrigerating the carbon dioxide in the tank during unusually long shut-down periods of the carbonators so that a storage tank having a working pressure of slightly higher value than the maximum pressure of the working range maintained in the system may be employed and so that the carbon dioxide remaining in storage during a shut-down period will be in proper condition to resume operation of the bottling plant.

Other objects and advantages of the invention will be apparent during the course of the following description.

In the accompanying drawings forming a part of this specification and in which like numerals

are employed to designate like parts throughout the same.

Figure 1 is a somewhat diagrammatic view of the apparatus of a bottling plant which operates to supply carbon dioxide vapors of substantially constant pressure to the pressure regulators of carbonators and to supply the drinking water, at a constant temperature, to the carbonators.

Figure 2 is a detail enlarged view, partly in section and partly broken away, of a coil structure employed in a heat exchanger included in the apparatus disclosed in Fig. 1.

Figure 3 is a diagrammatic view of the electric wiring system and automatic controls employed with the apparatus disclosed in Fig. 1, and

Figure 4 is a view similar to Fig. 1 but discloses a slightly modified form of apparatus.

In the drawings, wherein for the purpose of illustration are shown the preferred embodiments of this invention, and particularly referring to Fig. 1, the reference character 5 designates a bulk storage tank which is completely enclosed within the relatively thick layer of insulating material 6 for the purpose of retarding to the greatest extent possible the input of heat from the surrounding atmosphere. The capacity of the bulk storage tank 5 may be that which is most suitable for the bottling plant in which the apparatus embodying this invention is installed. The largest tank so far installed has a capacity for 125 tons of liquid carbon dioxide. However, tanks of considerably lower capacity; i. e., tanks holding 3½, 6, and 8 tons, provide an ample supply of carbon dioxide for many beverage bottling plants.

The ability to employ single bulk storage tanks for the amount of carbon dioxide required by a bottling plant is dependent upon maintaining the stored liquid carbon dioxide below a predetermined maximum pressure which is well below the vapor pressure of liquid carbon dioxide at room temperature, or 70° F. Pressure tanks having A. S. M. E. pressure ratings of 325 pounds have been found to be entirely satisfactory if the maximum pressure maintained in the tank does not exceed approximately 300 pounds per square inch.

To prevent the vapor pressure of the liquid carbon dioxide stored in the tank 5 from exceeding approximately 300 pounds per square inch, a refrigerating coil 7 is located in the vapor space of the tank. This coil is connected by the pipe lines 7' to any standard make of mechanical refrigerating plant which has a sufficient capacity for the particular tank involved. No attempt has been made to illustrate such a refrigerating plant as the details of such a plant form no part of this invention. The refrigerating coil 7 functions to condense carbon dioxide vapors in the vapor space of the tank 5 and return the drops of condensation to the liquid bath within the tank.

If a maximum pressure of 300 pounds per square inch is to be maintained in the bulk storage tank 5, the carbon dioxide delivered to the bottling plant is transported in bulk and is charged into the storage tank 5 from the transportation vehicles at a pressure which will not materially exceed the maximum pressure to be maintained within the tank 5. In transferring the liquid carbon dioxide from the transport vehicle to the storage tank 5, the liquid spaces of the two tanks are placed in communication by any suitable piping, not shown,

and a pump may be employed in this piping to effect the transfer. The vapor spaces of the two tanks, also, are placed in open communication with each other, and Fig. 1 of the drawings shows a vapor line 8 with a branch line 9 for this purpose.

Suitable bleeder valves and safety disc are provided for the bulk storage tank 5 to prevent a dangerous rise in pressure within the tank in case the refrigerating apparatus, not shown, connected to the cooling coil 7 is rendered inoperative for any reason.

For the purpose of delivering carbon dioxide from the bulk storage tank 5 to the carbonators of the beverage bottling plant, it is the purpose of this invention to alternately withdraw carbon dioxide vapors and liquid. The vapor line 8, with the branch line 9 properly closed, serves for the withdrawal of vapors. A liquid line 10 is provided for withdrawing liquid carbon dioxide from a point relatively close to the bottom of the tank 5.

The vapor line includes a shut off valve 11 which is manually operated and a solenoid valve 12 which may be manually operated but which is normally operated as a result of a predetermined minimum pressure prevailing within the tank 5. A pressure operated mercoid switch 13 is placed in communication with the vapor line 8 for a purpose to be explained at a later point.

The liquid line 10 has connected therein a manually operable valve 14 and a second valve 15 which may be manually operated but which normally is operated by means of a solenoid. The two branch lines 8 and 10 are connected to a common carbon dioxide pipe line 16 which extends to and is connected with a strainer 17, having a drain 18 controlled by the valve 19. From the strainer 17, a carbon dioxide line 20 extends to and is suitably connected with the inner tube of a double tube heat exchanger coil 21. Fig. 2 discloses the construction of this heat exchanger coil. It consists of a relatively small inner tube 22 for the carbon dioxide and a larger tube 23 which is connected to a source of supply of a fluid having a temperature considerably higher than the temperature of the carbon dioxide delivered to the inner tube of the coil from the bulk storage tank 5.

From the lower discharge end of the heat exchanger coil 21, a pipe line 24 is provided for carrying away the carbon dioxide. Connected in this line 24 is a shut off valve 25. Beyond the valve is a manifold 26 to which a bank of carbon dioxide cylinders 27 may be connected. From the manifold, a pipe line 28 extends to the coil 29 of a heater 30 which includes a gas jet 31 as the source of heat. From the heating coil 29, a pipe line 32 extends to and is connected with a plurality of branch lines 33 which lead to carbonators, not shown. In each one of these branch lines 33 there is located a pressure regulator 34 which takes the form of a pressure reducing valve.

In the form of the invention shown in Fig. 1, the fluid employed for heating the carbon dioxide flowing through the heat exchanger coil 21 is the drinking water which is employed in the carbonators. The reference character 35 designates a pipe line which bears the legend "City water line." It is to be understood, however, that this pipe line 35 may extend from any other suitable source of supply, such as a private well owned by or controlled by the bottling company. This water supply line 35 is connected by a

branch line 36 to the outer tube 23 of the heat exchanger coil 21. The lower end of this outer tube 23 is connected to a coupling 37 which has joined thereto a line 38. A T-coupling 39 joins the line 38 to a bypass line 40 and an extension 41 to the line 38.

A combined shut off valve and air vent 42 is connected in the pipe line 36. A drain valve 43 is connected to the line 38, and the outer tube 23 of the heat exchanger coil 21, by means of the coupling 37. A shut off valve 44 is connected in the pipe line 41. The by-pass line has connected therein a solenoid valve 45 and a manually controlled throttling valve 46. This by-pass line 40 is intended to extend to a suitable drain, or the like, for discharging into a sewer or other means of disposal.

The upper ends of the lines 36 and 41 are interconnected by a by-pass 47 which is controlled by the valve 48. From the T-coupling 49, which joins the line 41 with the by-pass 47, a pipe line 50 conducts the water to a filter 51. The water discharged from the filter is carried by the line 52 to a discharge point 53 where the water is delivered to a cooling coil 54 that is supplied with a refrigerating brine by means of the pipe lines 55. The water, after passing over the cooling coil 54, is collected in a basin 56 and is delivered to a cold water storage tank 57. A valve 58 is located in the water line 52 and is controlled by a float 59 so that the passage of water through the line 52 to the point of discharge 53 onto the cooling coil 54 is stopped when the water in the storage tank 57 reaches a predetermined level. From the storage tank, the water, at the desired low temperature, is delivered to the carbonators through the pipe line 60.

A float operated switch 61 is located in the water storage tank 57 and, as will be explained at a later point, operates to control the flow of electricity to an electric motor which drives the brine pump for the lines 55 and also controls the flow of electricity to the coil of the solenoid valve 45 located in the by-pass 40.

Before explaining the mode of operation of the apparatus disclosed in Fig. 1, it is believed to be desirable to first explain the wiring diagram of Fig. 3. The main supply lines of this wiring system are designated by the reference characters 61, 62, and 63. These lines extend to a triple pole, single throw switch 64 which may be manually operated to control the periods of operation or periods of supply of electricity to the refrigerating apparatus for the bulk storage tank 5 and the carbon dioxide vapor and liquid solenoid valves 12 and 15.

Extending from the switch 64 to the motor starter switch or box 65 of the refrigerator motor 66 are the three wires 61a, 62a, and 63a. This refrigerator motor 66 operates the refrigerating apparatus which is connected to the vapor condensing coil 7 located in the bulk storage tank 5. The refrigerator motor 66 is started and stopped in response to a pressure operated mercoid switch 67 which is suitably associated with the bulk storage tank 5 but not disclosed structurally in connection therewith. A manual control switch 68 is provided to render the refrigerator motor controlling mercoid switch 67 inoperative.

Connected to the branch lines 62a and 63a are wires 69 and 70 which form a circuit for the alarm bell 71 and the pressure gauge alarm contacts 72. This switch device 72 functions to sound the alarm bell 71 when the vapor pressure in the bulk storage tank 5 reaches a predeter-

mined maximum and a predetermined minimum.

Branch lines 73 and 74 extend from the lines 61a and 62a to a relay 75. A manual switch 76 is connected in the line 73 to render the relay 75 inoperative whenever necessary.

Coils 12a and 15a are associated with and controlled by the relay 75. The coil 12a is the coil for the solenoid valve 12, while the coil 15a is the coil for the solenoid valve 15. One side of each one of these coils 12a and 15a is connected to the branch line 73. These connections are obtained by the wires 77 and 78. The remaining side of the solenoid coil 12a is connected by the wire 79 to one side of a pair of switch contacts 80. The remaining contact of this pair is connected to a wire 81 which leads to the second branch wire 74. The second side of the solenoid coil 15a is connected to one contact of a switch 82 by means of the wire 83. The remaining contact of this second switch is connected by a wire 84 to the wire 81 leading to the branch line 74. Switch blades 85 and 86 are provided for the switch contacts 80 and 82 and these blades are connected to the armature for the solenoid 87 of the relay 75.

The coil of this solenoid 87 is in circuit with the wires 73 and 74 and includes a series connected, pressure operated mercury switch which is illustrated mechanically in Fig. 1 and bears the reference character 13. As the mercoind switch only forms a part of the element designated by the reference character 13 in Fig. 1, character 13a will be applied to the switch.

Branch lines 61b, 62b and 63b extend from the lines 61, 62, and 63. Flow of electricity through these branch lines is controlled by a triple pole, single throw manual switch 88. These three lines extend to a motor starter box or switch 89 from which extend the lines 90, 91, and 92 which lead to the electric motor that drives the brine pump connected to the pipes 55 of the cooling coil 54 for the drinking water. A manually operable switch 93 may be employed for controlling this motor of the brine pump. Automatic control of the starter switch 89 is obtained by means of the float controlled switch 61 that is operated by the water level in the storage tank 57.

It was stated above that the float controlled switch 61 also controlled the operation of the solenoid valve 45 for the water by-pass 40. The coil 45a of this solenoid valve is illustrated in this figure. The wire 94 extends from one side of this solenoid coil to the branch line 62b. The remaining side of this solenoid coil is connected by a wire 95 to the terminal 96 of the relay 97. The remaining terminal 98 of this relay has a wire 99 connected thereto which extends to the branch line 63b. The coil 100 of the relay 97 is connected to the lines 91 and 92 leading from the starter box or switch 89 for the brine pump motor by means of the wires 101 and 102. As a result of this connecting of the relay coil 100 in the lines 91 and 92 leading from the starter box 89 to the brine pump motor, the solenoid coil 45a will be energized for opening solenoid valve 45 to permit the water to flow through the by-pass 41 when the brine pump is stopped. This brine pump will be stopped when water ceases to flow through the line 52 to the point of discharge of the water onto the brine cooling coil 54 in response to actuation of the float controlled valve 58. When the brine pump is started, the solenoid coil 45 will be deenergized for closing the solenoid valve 45 to compel the water to flow

through the line 41 and the lines 50 and 52 to the brine cooling coil 54.

In describing the method carried out by the apparatus of Fig. 1, when controlled by the electrical instrumentalities and their circuits shown in Fig. 3, let us assume first that the pressure to be maintained in the carbonators; i. e., the carbon dioxide vapor pressure on the low pressure sides of the pressure regulators 34, is 45 pounds per square inch. The pressure in the bulk storage tank will not be permitted to build up to a value over 300 pounds during a prolonged shutdown period. At 300 pounds, the mercoind switch 67 will be actuated for starting the refrigerator motor 66 by means of the motor starter 65. Actuation of the refrigerator connected to the cooling coil 7 by the pipe lines 8 will result in condensing the vapors in the vapor space of the bulk storage 5 until the pressure therein has been reduced to, say 275 or 280 pounds per square inch. If the pressure within the bulk storage tank 5 is not permitted to rise above approximately 300 pounds per square inch, the temperature of the carbon dioxide within the bulk storage tank will not rise above 0° F.

It has been ascertained that very satisfactory maximum and minimum pressures for the narrow pressure range to be maintained in the bulk storage tank during periods of operation are 225 and 200 pounds per square inch. For the maximum pressure of 225 pounds, the temperature of the carbon dioxide within the tank 5 will be approximately -18° F. For the minimum pressure of 200 pounds, the temperature of the carbon dioxide will be approximately -24° F.

With this spread of 75 pounds between the maximum operating pressure of 225 pounds and the pressure at which the refrigerator for the tank 5 cuts in, i. e., at 300 pounds, the normal rate of input of heat through the insulation for the tank 5 will allow a period of approximately 60 hours before the refrigerator will be called upon to lower the pressure within the bulk storage tank. It will be apparent, therefore, that the plant may operate on a five day week and be shut down for 48 hours over a week end without requiring operation of the refrigerator for the stored carbon dioxide.

Let us now assume that at the time of starting operations on a Monday morning, the pressure within the tank 5 is at approximately 275 pounds. At this pressure, the circuit through the mercoind switch 13a is closed and the solenoid coil 12a for the valve 12 is energized. This valve 12, therefore, is open and the solenoid valve 15 is closed. Carbon dioxide vapors will flow through the line 8 and the line 16 to the strainer 17. From the strainer the vapors will flow through the line 20 to the inner tube 22 of the heat exchanger coil 21. In passing through this coil, the carbon dioxide vapors will be placed in heat exchange relation with the city water which flows through the line 35 and the line 36 to the outer tube 23 of the coil 21. Valves 42 and 45 are open to allow for this flow of city water. The valve 48 is normally closed.

The carbon dioxide vapors and the drinking water will flow concurrently, downwardly through the heat exchanger coil 21 and the vapors will absorb sufficient heat from the water to place these two flowing fluids at approximately the same temperature. The carbon dioxide vapors will be superheated and the water will be cooled. The pressure of the superheated carbon dioxide

vapors will be the same as the pressure prevailing within the bulk storage tank 5.

The carbon dioxide vapors, as they leave the heat exchanger coil 21, will flow through the lines 24 and 28 to the coil 29 of the heater 30 and from this coil through the line 32 to the several branch lines 33. The gas burner 31 for the heater 30 will not be in operation because the temperature of the carbon dioxide vapors flowing from the heat exchanger to the pressure regulators 34 will be sufficiently high to prevent freezing of water vapors as a result of the throttling effect produced by the regulators 34. It will be appreciated that there is no likelihood of water vapors freezing in the pressure regulators 34 because there is practically no water vapor in the extremely low temperature carbon dioxide in the tank 5; because the heat exchanger coil 21 elevates the temperature of the vapors to at least the temperature of the water passing through the coil; and because the pressure drop produced by the regulators 34 is not sufficient to produce a throttling effect that will lower the temperature of the vapors below 32° F.

The solenoid valve 12 for the vapor line 8 will remain open until the pressure within the bulk storage tank 5 drops to 200 pounds as a result of self-refrigeration of the liquid within the tank. It will be understood that this self-refrigeration is brought about by the evaporation of liquid within the tank to provide vapors to take the place of the vapors withdrawn through the line 8.

When the pressure in the tank reaches the minimum of 200 pounds, the mercoil switch 13a is actuated to break the circuit to the solenoid coil 87 and the switch blades 85 and 86 assume the positions illustrated in Fig. 3. When this action takes place, the circuit is closed through the solenoid coil 15a for the valve 15 and the circuit is broken through the solenoid coil 12a for the valve 12. From then on, liquid carbon dioxide flows through the liquid line 10 and the line 16 into the strainer 17 and then through the line 20 into the heat exchanger coil 21.

The liquid carbon dioxide passing through the heat exchanger must be converted to vapor and the drinking water passing through the heat exchanger coil gives up heat of vaporization to the carbon dioxide to accomplish that result. If the heat exchanging capacity of the coil 21 is sufficient, the liquid carbon dioxide will not only be converted to vapor, but the temperatures of the drinking water and the resultant carbon dioxide vapors will be equalized. When this occurs, the water will be cooled to a lower temperature than when carbon dioxide vapors are being withdrawn from the tank 5.

The carbon dioxide vapors will flow from the heat exchanger coil 21 through the lines 24 and 28 to the heater coil 29 and from this coil through the line 32 to the pressure regulators 34 in the branch lines 33. Whether the gas burner 31 will be required to further heat these carbon dioxide vapors as they flow through the heater coil 29 will depend entirely upon the capacity of the heat exchanger 21 to raise the temperature of the vapors and, of course, the original temperature of the water flowing into the heat exchanger through the lines 35 and 36.

The foregoing explanation traces out the normal operation of the system to deliver carbon dioxide vapors to the pressure regulators 34 and it will be appreciated that the pressure of the vapors delivered to the high pressure sides of the regulators will not vary over 25 pounds throughout

the entire range of operation. The complete cycle for the drinking water being delivered to the carburetors now will be explained.

The water, as was stated above, normally flows through the lines 35 and 36 to the exchanger coil 21. From the lower discharge end of the outer tube 23, the water passes into the line 38 and flows from the discharge side of the T-coupling 39 through the lines 41 and 50 into the filter 51. From the filter, the water flows through the line 52 to its point of discharge 53 onto the brine cooling coil 54. The coil 54 will function to lower the temperature of the water to the desired value, which we shall assume is 33° F. The water will continue to flow in this manner until the level in the storage tank 51 reaches the point where the float 59 will close the valve 58. At this level, the float for the switch 61 will actuate this switch for energizing the circuit to the coil 45a of the solenoid valve 45. This valve will be opened and the water then will flow from the line 38 into the by-pass 40 and be discharged into a suitable drain, or the like. The float actuated switch 61, also, will open the circuit through the lines 90, 91, and 92 which lead to the electric motor of the brine pump connected to the pipe lines 55. The water will be discharged through the by-pass 40 into the drain until a sufficient amount of water has been withdrawn from the storage tank 51 through the pipe line 60 and delivered to the carbonators to lower the level within the tank 51 sufficiently to open the valve 58 and close the switch 61.

In describing the solenoid valves 12 and 15, it was stated that they could be manually operated if so desired. This manual operation is provided to take care of mechanical failure, or the like, of the mercoil switch 13a or the relay 75.

It has been ascertained that it is not absolutely essential to employ a mercoil switch in the carbon dioxide liquid line 10 to accomplish this alternate withdrawal of vapors and liquid. If the solenoid valve 15 is dispensed with, the solenoid valve 12 in the vapor line will function to control the flow of either vapor or liquid. When the valve 12 is open, vapor will flow through the line 8 and no liquid will flow through the line 10. This flow of only vapors results from the fact that the vapors will flow more readily than will the liquid if both phases of the carbon dioxide are placed in communication with a common discharge line. When the solenoid valve 12 is closed, in response to the pressure in the bulk storage tank 5 reaching the minimum value of 200 pounds, the flow of vapors will stop and liquid will be withdrawn from the tank.

The bank of carbon dioxide cylinders 27 is illustrated solely for the purpose of showing how this source of supply of high pressure carbon dioxide may be used to take care of any emergency break down of the low pressure source of supply. When carbon dioxide cylinders are to be employed, the valve 25 is closed and the valves for the several cylinders 27 are opened. The gas burner 31 must be used at all times when vapors are being withdrawn from the cylinders.

When the low pressure carbon dioxide supply is not being employed, the valves 42 and 44 are closed and the valve 48 is opened. The drinking water then flows from the pipe line 35 through the line 47 and into the line 50 leading to the filter 51. This water will not be cooled by passing in heat exchange relation to low temperature carbon dioxide in the coil 21 and for that reason the

water must be refrigerated to a greater extent in passing over the brine cooling coil 54.

To overcome any possibility of water remaining in the tube 23 of the heat exchanger coil 21 and the lines 36, 38, and 41, the closing of the water valve 42 opens the line 36 to the atmosphere. The drain valve 43 is opened to withdraw all water from this inactive part of the water circuit.

The valve 46 in the by-pass line 48 was described as a throttle valve. This valve is set to allow for the desired rate of flow of water through the heat exchanger coil 21 when the water is being dissipated down a drain.

The apparatus disclosed in Fig. 4 constitutes a slight modification of the apparatus disclosed in Fig. 1. In this system, carbon dioxide vapors and liquid alternately flow through the line 103 to the strainer 104, having a drain 105. This line 103, therefore, corresponds with the line 16 of the apparatus shown in Fig. 1. From the strainer 104, the carbon dioxide vapors or liquid flow through the line 106 into the lower end of the inner tube of the heat exchanger coil 107. The superheated carbon dioxide vapors leave the upper end of the heat exchanger coil through the line 108 and flows to the branch lines 109 controlled by the manual valves 110. Electric heaters 111 are connected to the lines 109. These heaters function in the same manner as the heater 38, of Fig. 1, with its gas burner 34. From the electric heaters, the carbon dioxide vapors flow to the pressure regulators 112, located in the lines 113, and from these regulators to the carbonators.

In this installation, the supply of drinking water for the carbonators is not connected to the heat exchanger coil 107 but instead some other source of supply of a heating fluid is substituted and is connected to the lower end of the outer tube of the heat exchanger coil 107 by the pipe line 114. In certain installations which have been made, the pipe line 114 is connected to a well which yields water that is colder than the water coming from the regular city water main.

This cold well water is discharged from the upper end of the outer tube of the heat exchanger coil 107 through the line 115 into a cooling coil 116 located in the chamber 117. From the remaining end of this cooling coil 116, the well water is carried away by the pipe line 118 and is dissipated down a drain or is delivered to some other suitable place of use or disposal.

The drinking water coming from the city main is delivered to the apparatus through the pipe line 119 and, after passing through the filters 120, is delivered to the spray head 121 located in this cooling chamber 117. A solenoid valve 122 controls the flow of water to the spray head 121, and this solenoid valve is controlled by the liquid level in the cold water storage tank, not shown, but corresponding with the tank 57 of Fig. 1.

To further cool the water delivered to the chamber 117, a brine, or other refrigerant, coil 123 is located in the chamber and is connected to the refrigerating apparatus by the lines 124. The properly cooled water is withdrawn from the bottom of the chamber 117 through the pipe line 125 and is delivered to the cold water storage tank.

It will be appreciated that this modified apparatus of Fig. 4 embodies three features which differ from the apparatus disclosed in Fig. 1.

The first feature deals with the concurrent upward flow of both the carbon dioxide and the

water through the heat exchanger coil 107. This upward flow is found to be desirable in some installations to prevent the carbon dioxide from passing too quickly through the heat exchanger.

The second feature embodies the use of a medium, cooler than the drinking water going to the cooling chamber 117, for first effecting heat exchange with the carbon dioxide and then effecting heat exchange with the drinking water. As a result of the first heat exchange, the carbon dioxide will be warmed and the cooling medium will be rendered even cooler than it was upon entering the coil 107. The second heat exchanger, therefore, will be more effective than would be the case if the original temperature of the medium flowing through pipe 114 were employed in coil 116.

The third feature embodies the use of electric heaters in place of the gas heater shown in Fig. 1. It will be appreciated that steam heaters might also be employed instead of the gas heater of Fig. 1 and the electric heaters of Fig. 4.

In case it is necessary to resort to the use of high pressure carbon dioxide cylinders in place of the low temperature source of supply, the branch line 126 is tapped into the carbon dioxide line 108 downstream from the heat exchanger 107.

It is to be understood that the forms of this invention herewith shown and described are to be taken as preferred examples of the same, and that various changes in the shape, size, and arrangement of parts may be resorted to without departing from the spirit of the invention or the scope of the subjoined claims.

Having thus described the invention, I claim:

1. A method of conditioning and supplying carbon dioxide to carbonators, comprising maintaining a supply of liquid carbon dioxide in bulk storage in a heat insulated tank, withdrawing carbon dioxide vapors from the supply until the self-cooling effect of such withdrawal lowers the vapor pressure in the tank to a predetermined minimum value, after said minimum value has been reached, stopping withdrawal of vapors and withdrawing liquid carbon dioxide from the supply until the vapor pressure in the tank rises to a predetermined maximum value as a result of heat input through the tank insulation and the absence of any self-cooling effect, repeating the aforesaid cycle of alternately withdrawing vapors and liquid as long as carbon dioxide is being withdrawn from the supply to maintain the vapor pressure in the tank between said maximum and minimum values, passing the liquid carbon dioxide vapor and liquid in heat exchange relation to the flow of drinking water going to the carbonators to effect cooling of the said water as a result of giving up heat of vaporization to the liquid carbon dioxide and superheating the thus formed vapor and the vapor obtained directly from the tank and delivering all of the withdrawn carbon dioxide to the pressure regulators of carbonators as superheated vapor at pressures falling between said maximum and minimum values.

2. A method of conditioning and supplying carbon dioxide to carbonators, comprising maintaining a supply of liquid carbon dioxide in bulk storage in a heat insulated tank, withdrawing carbon dioxide vapors from the supply until the self-cooling effect of such withdrawal lowers the vapor pressure in the tank to a predetermined minimum value, after said minimum value has been reached, stopping withdrawal of vapors and

withdrawing liquid carbon dioxide from the supply until the vapor pressure in the tank rises to a predetermined maximum value as a result of heat input through the tank insulation and the absence of any self-cooling effect, repeating the aforesaid cycle of alternately withdrawing vapors and liquid as long as carbon dioxide is being withdrawn from the supply to maintain the vapor pressure in the tank between said maximum and minimum values, and delivering all of the withdrawn carbon dioxide to the pressure regulators of carbonators as vapor at pressures falling between said maximum and minimum values and in a superheated condition, the pressure and superheated condition of the vapor delivered to said pressure regulators being such as to prevent the freezing of any water particles which may be in the vapors as a result of the pressure drop at the regulators.

3. A method of conditioning and supplying carbon dioxide to carbonators, comprising maintaining a supply of liquid carbon dioxide in bulk storage in a heat insulated tank, withdrawing carbon dioxide vapors from the supply until the self-cooling effect of such withdrawal lowers the vapor pressure in the tank to a predetermined minimum value, after said minimum value has been reached, stopping withdrawal of vapors and withdrawing liquid carbon dioxide from the supply until the vapor pressure in the tank rises to a predetermined maximum value as a result of heat input through the tank insulation and the absence of any self-cooling effect, repeating the aforesaid cycle of alternately withdrawing vapors and liquid as long as carbon dioxide is being withdrawn from the supply to maintain the vapor pressure in the tank between said minimum and maximum values, evaporating the liquid carbon dioxide withdrawn from the source to obtain vapors, and delivering the thus formed vapors and the vapors withdrawn directly from the source to pressure regulators of carbonators at pressures falling between said minimum and maximum values and in a superheated condition, the pressure and superheated condition of the vapor delivered to said pressure regulators being such as to prevent the freezing of any water particles which may be in the vapors as a result of the pressure drop at the regulators.

4. A method of conditioning and supplying carbon dioxide to carbonators, comprising maintaining a supply of liquid carbon dioxide in bulk storage in a heat insulated tank, withdrawing carbon dioxide vapors from the supply until the self-cooling effect of such withdrawal lowers the vapor pressure in the tank to a predetermined minimum value, after said minimum value has been reached, stopping withdrawal of vapors and withdrawing liquid carbon dioxide from the supply until the vapor pressure in the tank rises to a predetermined maximum value as a result of heat input through the tank insulation and the absence of any self-cooling effect, repeating the aforesaid cycle of alternately withdrawing vapors and liquid as long as carbon dioxide is being withdrawn from the supply to maintain the vapor pressure in the tank between said maximum and minimum values, passing the carbon dioxide vapor and liquid in heat exchange relation to the flow of drinking water going to the carbonators to effect cooling of the said water as a result of giving up heat of vaporization to the liquid carbon dioxide and superheating the thus formed vapor and the vapor obtained directly from the tank, delivering all of

the withdrawn carbon dioxide to the pressure regulators of carbonators as superheated vapor at pressures falling between said maximum and minimum values, and refrigerating the carbon dioxide in said tank to prevent a substantial rise in vapor pressure above the aforesaid maximum value if the amount of vapor withdrawn from the tank during any given period is not sufficient to prevent such rise.

5. A method of conditioning and supplying carbon dioxide to carbonators, comprising maintaining a supply of liquid carbon dioxide in bulk storage in a heat insulated tank, withdrawing carbon dioxide vapors from the supply until the self-cooling effect of such withdrawal lowers the vapor pressure in the tank to a predetermined minimum value, after said minimum value has been reached, stopping withdrawal of vapors and withdrawing liquid carbon dioxide from the supply until the vapor pressure in the tank rises to a predetermined maximum value as a result of heat input through the tank insulation and the absence of any self-cooling effect, repeating the aforesaid cycle of alternately withdrawing vapors and liquid as long as carbon dioxide is being withdrawn from the supply to maintain the vapor pressure in the tank between said minimum and maximum values, evaporating the liquid carbon dioxide withdrawn from the source to obtain vapors, delivering the thus formed vapors and the vapors withdrawn directly from the source to pressure regulators of carbonators at pressures falling between said minimum and maximum values, and refrigerating the carbon dioxide in said tank to prevent a substantial rise in vapor pressure above the aforesaid maximum value if the amount of vapor withdrawn from the tank during any given period is not sufficient to prevent such rise.

6. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, delivering all of the withdrawn carbon dioxide to the pressure regulators of carbonators as vapor at pressures falling between said maximum and minimum values, and refrigerating the carbon dioxide in said tank to prevent a substantial rise in vapor pressure above the aforesaid maximum value if the amount of vapor withdrawn from the tank during any given period is not sufficient to prevent such rise.

7. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, evaporating the liquid carbon dioxide withdrawn from the source to obtain vapors, delivering the thus formed vapor and the vapor withdrawn directly from the source to the pressure regulators of carbonators at pressures falling between said maximum and minimum values and in a superheated condition, the pressure and superheated condition of the vapor delivered to said pressure regulators being such as to prevent the freezing of any water particles

which may be in the vapors as a result of the pressure drop at the regulators, and refrigerating the carbon dioxide in said tank to prevent a substantial rise in vapor pressure above the aforesaid maximum value if the amount of vapor withdrawn from the tank is not sufficient during any given period to prevent such rise.

8. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to a fluid having a sufficiently higher temperature value to give up heat of vaporization to the liquid carbon dioxide and to superheat the thus formed vapor and the vapor obtained directly from the tank, and delivering the superheated vapor to the pressure regulators of carbonators at pressures falling between the aforesaid maximum and minimum values, the pressure and superheated condition of the vapor delivered to said pressure regulators being such as to prevent the freezing of any water particles which may be in the vapors as a result of the pressure drop at the regulators.

9. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to and concurrently upwardly with a fluid having a sufficiently higher temperature value to give up heat of vaporization to the liquid carbon dioxide and to superheat the thus formed vapor and the vapor obtained directly from the tank, and delivering the superheated vapor to the pressure regulators of carbonators at pressures falling between the aforesaid maximum and minimum values and in their superheated condition, the pressure and superheated condition of the vapor delivered to said pressure regulators being such as to prevent the freezing of any water particles which may be in the vapor as a result of the pressure drop at the regulators.

10. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to the flow of drinking water going to the carbonators to effect cooling of the said water as a result of giving up heat of vaporization to the liquid carbon dioxide and superheating the thus formed vapor and the vapor obtained directly from the tank, and delivering the superheated vapor to the pressure regulators of carbonators at pressures falling between the aforesaid maximum and minimum values.

11. A method of conditioning and supplying carbon dioxide to carbonators, comprising main-

taining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to a fluid having a sufficiently higher temperature value to give up heat of vaporization to the liquid carbon dioxide and to superheat the thus formed vapor and the vapor obtained directly from the tank, delivering the superheated vapor to the pressure regulators of carbonators at pressures falling between the aforesaid maximum and minimum values, the pressure and superheated condition of the vapor delivered to said pressure regulators being such as to prevent the freezing of any water particles which may be in the vapors as a result of the pressure drop at the regulators, and refrigerating the carbon dioxide in the tank to prevent a substantial rise in vapor pressure above the aforesaid maximum value if the amount of vapor withdrawn from the tank during any given period is not sufficient to prevent such rise.

12. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to the flow of drinking water going to the carbonators to effect cooling of the said water as a result of giving up heat of vaporization to the liquid carbon dioxide and superheating the thus formed vapor and the vapor obtained directly from the tank, delivering the superheated vapor to the pressure regulators of carbonators at pressures falling between the aforesaid maximum and minimum values, and refrigerating the carbon dioxide in said tank to prevent a substantial rise in vapor pressure above the aforesaid maximum value if the amount of vapor withdrawn from the tank during any given period is not sufficient to prevent such rise.

13. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to a fluid having a sufficiently higher temperature value to give up heat of vaporization to the liquid carbon dioxide and to superheat the thus formed vapor and the vapor obtained directly from the tank, passing the thus cooled heat exchanger liquid in heat exchange relation to the flow of drinking water going to the carbonators, and delivering the superheated carbon dioxide vapors and the drinking water to said carbonators.

14. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure

variations in the tank falling between maximum and minimum values which define a relatively narrow range, passing the carbon dioxide vapor and liquid in heat exchange relation to a fluid having a sufficiently higher temperature value to give up heat of vaporization to the liquid carbon dioxide and to superheat the thus formed vapor and the vapor obtained directly from the tank, passing the thus cooled heat exchanger liquid in heat exchange relation to the flow of drinking water going to the carbonators, delivering the superheated carbon dioxide vapors and the drinking water to said carbonators, and refrigerating the carbon dioxide in said tank to prevent a substantial rise in vapor pressure above the aforesaid maximum value if the amount of vapor withdrawn from the tank during any given period is not sufficient to prevent such rise.

15. Apparatus for conditioning and supplying carbon dioxide to carbonators, comprising a heat insulated bulk storage tank for liquid carbon dioxide, vapor and liquid draw off lines extending from said tank, valve means for effecting alternate withdrawal of vapor and liquid from said tank in response to variations in vapor pressure in the tank falling between maximum and minimum values which define a relatively narrow range, a heat exchanger, means for delivering both the vapors and the liquid to said heat exchanger, means for delivering to said heat exchanger drinking water going to the carbonators which has a sufficiently high temperature to give up heat of vaporization to the liquid carbon dioxide and to superheat the thus formed vapor and the vapor obtained directly from the tank, and pressure regulators for carbonators connected to the heat exchanger to receive the superheated vapors.

16. Apparatus for conditioning and supplying carbon dioxide to carbonators, comprising a heat insulated bulk storage tank for liquid carbon dioxide, vapor and liquid draw off lines extending from said tank, valve means for effecting alternate withdrawal of vapor and liquid from said tank through said lines in response to variations in vapor pressure in the tank falling between maximum and minimum values which define a relatively narrow range, a heat exchanger, means for delivering both the vapors and the liquid to said heat exchanger, means for passing the drinking water going to the carbonators through the heat exchanger to effect cooling of the water as a result of vaporizing the liquid carbon dioxide and to effect superheating of the carbon dioxide vapors, means for delivering the superheated vapors to the pressure regulators of carbonators, a water storage tank, means for feeding the cooled water from the heat exchanger to the water storage tank, means for by-passing the cooled water leaving the heat exchanger into a drain when the water storage tank is filled, means for further refrigerating the cooled water delivered to the water storage tank from the heat exchanger, and means for delivering the water from the storage tank to the carbonators.

17. Apparatus for conditioning and supplying carbon dioxide to carbonators, comprising a heat insulated bulk storage tank for liquid carbon dioxide, vapor and liquid draw off lines extending from said tank, valve means for effecting alternate withdrawal of vapor and liquid from said tank through said lines in response to variations in vapor pressure in the tank falling be-

tween maximum and minimum values which define a relatively narrow range, a heat exchanger, means for delivering both the vapors and the liquid to said heat exchanger, means for passing the drinking water going to the carbonators through the heat exchanger to effect cooling of the water as a result of vaporizing the liquid carbon dioxide and to effect superheating of the carbon dioxide vapors, means for delivering the superheated vapors to the pressure regulators of carbonators, a water storage tank, means for feeding the cooled water from the heat exchanger to the water storage tank, means for by-passing the cooled water leaving the heat exchanger into a drain when the water storage tank is filled, means for further refrigerating the cooled water delivered to the water storage tank from the heat exchanger, means for delivering the water from the storage tank to the carbonators, and means for refrigerating the carbon dioxide in said storage tank when the vapor pressure in the tank reaches a predetermined value above the maximum value of the aforesaid narrow range.

18. Apparatus for conditioning and supplying carbon dioxide to carbonators, comprising a heat insulated bulk storage tank for liquid carbon dioxide, vapor and liquid draw off lines extending from said tank, valve means for effecting alternate withdrawal of vapor and liquid from said tank through said lines in response to variations in vapor pressure in the tank falling between maximum and minimum values which define a relatively narrow range, a heat exchanger, means for delivering both the vapors and the liquid to said heat exchanger, means for passing the drinking water going to the carbonators through the heat exchanger to effect cooling of the water as a result of vaporizing the liquid carbon dioxide and to effect superheating of the carbon dioxide vapors, means for delivering the superheated vapors to the pressure regulators of carbonators, a water storage tank, means for feeding the cooled water from the heat exchanger to the water storage tank, means for further refrigerating the cooled water delivered to the water storage tank from the heat exchanger, and means for delivering the water from the storage tank to the carbonators.

19. Apparatus for conditioning and supplying carbon dioxide to carbonators, comprising a heat insulated bulk storage tank for liquid carbon dioxide, vapor and liquid draw off lines extending from said tank, valve means for effecting alternate withdrawal of vapor and liquid from said tank through said lines in response to variations in vapor pressure in the tank falling between maximum and minimum values which define a relatively narrow range, a heat exchanger, means for delivering both the vapors and the liquid to said heat exchanger, means for passing the drinking water going to the carbonators through the heat exchanger to effect cooling of the water as a result of vaporizing the liquid carbon dioxide and to effect superheating of the carbon dioxide vapors, means for delivering the superheated vapors to the pressure regulators of the carbonators, and means for refrigerating the carbon dioxide in said storage tank when the vapor pressure in the tank reaches a predetermined value above the maximum value of the aforesaid narrow range.

20. Apparatus for conditioning and supplying carbon dioxide to carbonators, comprising a heat

insulated bulk storage tank for liquid carbon dioxide, vapor and liquid draw off lines extending from said tank, valve means for effecting alternate withdrawal of vapor and liquid from said tank through said lines in response to variations in vapor pressure in the tank falling between maximum and minimum values which define a relatively narrow range, a heat exchanger, means for delivering both the vapors and the liquid to said heat exchanger, means for passing the drinking water going to the carbonators through the heat exchanger to effect cooling of the water as a result of vaporizing the liquid carbon dioxide and to effect superheating of the carbon dioxide vapors, means for delivering the superheated vapors to the pressure regulators of the carbonators, a water storage tank, means for feeding the cooled water from the heat exchanger to the water storage tank, means for further refrigerating the cooled water delivered to the water storage tank from the heat exchanger, and means for delivering the water from the storage tank to the carbonators.

21. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, passing the carbon dioxide vapor and liquid in heat exchange relation to and concurrently upwardly with a fluid having a sufficiently higher temperature value to give up heat or vaporization to the liquid carbon dioxide and to superheat the thus formed vapor and the vapor obtained directly from the tank, passing the thus cooled heat exchanger liquid in heat exchange relation to the flow of drinking water going to the carbonators, and delivering the superheated vapor to the pressure regulators of

carbonators at pressures falling between the aforesaid maximum and minimum values and in their superheated condition.

22. A method of conditioning and supplying carbon dioxide to carbonators, comprising maintaining a supply of liquid carbon dioxide in bulk storage in a heat insulated tank, withdrawing carbon dioxide vapors from the supply until the self-cooling effect of such withdrawal lowers the vapor pressure in the tank to a predetermined minimum value, after said minimum value has been reached, stopping withdrawal of vapors and withdrawing liquid carbon dioxide from the supply until the vapor pressure in the tank rises to a predetermined maximum value as a result of the heat input through the tank insulation and in the absence of any self-cooling effect, repeating the aforesaid cycle of alternately withdrawing vapors and liquid as long as carbon dioxide is being withdrawn from the supply to maintain the vapor pressure in the tank between said minimum and maximum values, evaporating the liquid carbon dioxide withdrawn from the source to obtain vapors, and delivering the thus formed vapors and the vapors withdrawn directly from the source to pressure regulators of carbonators at pressures falling between said minimum and maximum values.

23. A method of conditioning and supplying carbon dioxide to carbonators, comprising maintaining a supply of liquid carbon dioxide in bulk storage in a heat insulated tank, alternately withdrawing carbon dioxide vapor and liquid from the tank in response to vapor pressure variations in the tank falling between maximum and minimum values which define a relatively narrow range, and delivering all of the withdrawn carbon dioxide to the pressure regulators of carbonators as vapor at pressures falling between said maximum and minimum values.

CHARLES A. GETZ.
